UNITED STATES PATENT OFFICE

BERNARD F. SHAUGHNESSY, OF BROOKLYN, NEW YORK

GAS SEPARATOR

Original application filed October 7, 1925, Serial No. 60,960. Divided and this application filed November 7, 1927. Serial No. 231,661.

The present invention relates to gas separators, and aims to provide a novel and improved gas separating means particularly useful for incinerators for burning garbage and other refuse, this application being a division of the application for patent on incinerators, filed Oct. 7, 1925, Serial No. 60,960 (now Patent No. 1,651,636, granted Dec. 6, 1927).

It is the object of the invention to provide novel means for separating from the gas which is discharged to the atmosphere, the unburned particles, such as contained in smoke and green gases, in order to prevent the gases discharged into the atmosphere from being obnoxious. The unburned material or particles are arrested, thereby preventing excessive soot and obnoxious gases from passing into the atmosphere, making the incinerator available for use in localities which strictly require incinerators to burn without offensive smoke or smell.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawings, wherein—

Figure 1 illustrates an incinerator, partly in side elevation and partly in vertical section, including the improved gas separator.

Fig. 2 is a vertical section on the line 2—2 of Fig. 1.

Fig. 3 is a section on the line 3—3 of Fig. 1.

Fig. 4 is a vertical section on the line 4—4 of Fig. 5, corresponding to Fig. 2, and illustrating a modification.

Fig. 5 is a horizontal section on the line 5—5 of Fig. 4.

The furnace has a housing 59 at the rear

bustion pass, and in rear of the housing 59 is a second housing or chamber 74 extending from the housing 59 to the smoke stack 75. The partition or wall between the housings 59 and 74 has an opening 76, and the partition or wall between the housing 74 and stack 75 has an opening 77. A valve or damper 78 controls the opening 77.

Within the housing 74 between the openings 76 and 77 are means for separating the smoke and green gases from the flames and products of combustion passing along the center of the flue-way leading from the opening 76 to the opening 77. Thus, a flange 79 extends rearwardly from the side and upper edges of the opening 76, and a flange 81 extends forwardly from the side and upper edges of the opening 77. Between the flanges 79 and 81 are arches 80. The flanges 79 and 81 and arches 80 are spaced apart and are of gradually decreasing size rearwardly from the opening 76 to the opening 77, thereby having a tendency to compress the gases as they flow rearwardly to the stack. The flames and products of combustion pass through the central portion of the flue-way which leads through the members 79, 80 and 81 of the separating means, while the smoke and green gases move along the sides and top of the flue-way and will be deflected and crowded through the slots between the members 79, 80 and 81, thereby separating the smoke and green gases from the more complete products of combustion that pass into the stack 75 through the opening 77.

The housing 74 has a space 82 therein above the members or separators 79, 80 and 81, with an opening 83 leading into the smoke stack 75 and controlled by a damper or valve 84. The space 82 has another discharge opening 85 controlled by a damper or valve 86, and a suction fan 87 communicates with the opening 85 and has its discharge portion 88 delivering into the smoke stack. Disposed within the space 82 are grates or screens 89.

on which is disposed filtering material 90, which may be coke, cinders, soil, or other suitable material to arrest particles of soot, ashes and other solid material that enters the space 82.

- 5 The gases passing through the opening 76 from the furnace are separated, the valve or damper 78 being opened so that, in addition to the forced draft created by air discharged through the nozzle 54, there is a natural draft up the smoke stack 75. The flames and more complete products of combustion travel along the center of the stream, as is well known, and pass through the center 10 of the flue-way leading from the opening 76 to the opening 77, while the smoke and green gases moving along the sides and top of said flue-way pass through the slots between the separators 79, 80 and 81 into the space 82. 15 If the natural draft is sufficient then the damper 84 may be opened so that the natural draft will draw the smoke and green gases upwardly through the beds or layers 90 of filtering material which will arrest the particles of soot and other solid matter. If the natural draft is not sufficient for this purpose, then the fan 87 is operated to create a forced draft up through the layers 90 of filtering material, and the filtered gas is discharged from either opening 83 or 85 into the smoke stack. In this way, smoke and green gases are eliminated, so that the gases discharging from the smoke stack will not constitute a nuisance or be obnoxious. It will be noted that the flue-way is tapered or decreases in size from the opening 76 to the opening 77, thereby having a tendency to compress the gases flowing through said flue-way, and the smoke and green gases remaining 20 at the outside of the stream will be crowded through the slots or openings between the separators 79, 80 and 81 into the space 82. The draft extending through the space 82 will serve to draw the smoke and green gases from the separating means, so as not to impair the flow of gases from the furnace to the smoke stack, inasmuch as the gases flowing through the space 82 pass into the smoke stack through the opening 83 or 25 the opening 85 and fan 87. This draft through the space 82 will assist in drawing the smoke and green gases from the separating means through the filtering material 90. The filtering beds or layers 90 may be of any suitable area or extent necessary, preferably greater than the cross-sectional area of the smoke stack 75, so as not to impair the draft, and the filtering material may be removed and replaced as often as necessary. 30 The housing 74 has clean-out doors 91 in order that soot and other accumulations may be removed.

Figs. 4 and 5 illustrate variation in the means for removing the smoke and green gases from the products of combustion for

purposes of filtration. Thus, between the openings 76' and 77' is a passage or flueway 100 within the housing 74', through which passage the products of combustion flow to the smoke stack 75'. The passage 100 has openings 101 and 102 in its opposite sides which are arranged obliquely and in registration, as seen in Fig. 5. Cylindrical discharge heads 103 are disposed within the housing 74' adjacent to the openings 101 at the exterior of the passage 100 and have vertically spaced nozzles 104 directed into said openings toward the openings 102. The heads 103 are enclosed within the covers 105 which also close the openings 101 from the chamber of the housing 74'. The heads 103 are mounted for turning movement about vertical axes, and supply pipes 106 for steam, compressed air or other pressure fluid are connected by swivel connections with the upper ends of the heads 103 and have control valves 107. The lower ends of the heads 103 are geared, as at 108, to shafts 109 that have hand levers 110 which may be swung to turn the heads 103 and change the angular positions of the nozzles 104. The housing 74' has the space 82' in which the grates 89' are disposed to support the filtering material, and a suction fan 87' is located between the space 82' and smoke stack 75', the connections of the space 82' with the smoke stack being the same as shown in Fig. 1.

The steam, air or other fluid being discharged under pressure from the nozzles 104 is directed obliquely across the stream of products of combustion passing through the passage 100, and the streams of fluid from the nozzles passing through the openings 102 will intercept the particles of soot, thereby blowing the smoke and green gases through the openings 102 into the housing 74' so that the smoke and green gases will be filtered before passing through the smoke stack. The angular positions of the nozzles 104 may be adjusted according to the velocity of the products of combustion in flowing through the passage 100. It will be apparent that the fluid discharged from the nozzles from one side of the passage 100 will have a tendency to force the smoke and green gases toward the opposite side of the passage so as to pass readily through the openings 102, thereby separating such smoke and green gases from the products of combustion which pass through the opening 77' into the smoke stack 75'.

Having thus described the invention, what is claimed as new is:—

1. A gas separator comprising a flueway decreasing in size from its inlet to its outlet, a chamber at least partly surrounding said flueway, said flueway having a series of openings between it and said chamber for the flow into said chamber of the products of combustion which move along the outside of the stream.

passing through said flueway, and means for creating a forced draft from said flueway through said openings and chamber.

2. A gas separator including a flueway, a chamber at least partly surrounding said flueway, said flueway having a series of openings between its ends for the flow into said chamber of the products of combustion which move along the outside of the stream passing through said flueway, and means for creating a forced draft from said flueway through said openings and chamber.

In testimony whereof I hereunto affix my signature.

BERNARD F. SHAUGHNESSY.
